LOCKING-MECHANISM FOR BREAKDOWN FIREARMS

Louis Stiennon, deceased, late of New Haven, Conn., by Roy L. Parsell, administrator, Pine Orchard, Conn., assignor to Winchester Repeating Arms Company, New Haven, Conn., a corporation of Maryland

Application June 20, 1935, Serial No. 27,519

5 Claims. (Cl. 42—44)

This invention relates to improvement in breakdown firearms, that is to say, that class of firearms in which a barrel-unit and a butt-unit are hinged together for relative pivotal movement.

5 More particularly, the present invention relates to the mechanism by means of which the two units of the firearm above referred to are held against relative pivotal movement.

One of the objects of the present invention is 10 to provide a breakdown firearm with a superior locking-mechanism characterized by simplicity, ruggedness and economy of manufacture.

A further object of the present invention is 15 to provide a superior locking-mechanism for breakdown firearms which will accommodate itself to variations of manufacture and assembly.

A further object is to provide a superior locking-mechanism in which a locking-bolt carried by one of the relatively-pivoted units of the 20 firearm would automatically accommodate itself to variations in the locking-abutment of the complementary pivotal member of the firearm.

With the above and other objects in view, as 25 will appear to those skilled in the art from the following, considered in conjunction with the accompanying drawings and appended claims, the present invention includes all features disclosed therein which are novel over the prior art.

In the accompanying drawings:

30 Fig. 1 is a broken view partly in side elevation and partly in vertical section of a so-called "over-and-under" double-barreled shotgun in which the present invention is embodied, many parts not directly related to the present invention being omitted;

Fig. 2 is a broken top view thereof with the retaining-cap removed;

Fig. 3 is a broken horizontal sectional view taken on the line 3—3 of Fig. 1;

40 Fig. 4 is a broken vertical sectional view taken on the line 4—4 of Fig. 1;

Fig. 5 is a vertical sectional view taken on the line 5—5 of Fig. 1;

Fig. 6 is a perspective view showing the operating-lever, coupling-head, locking-bolts and associated parts in related positions, looking mainly toward the under-side thereof;

Fig. 7 is a perspective view of the two complementary locking-bolts and the coupling-head, looking mainly toward the under-side thereof and shown as separated for clarity of illustration;

Fig. 8 is a perspective view of the operating-lever looking mainly toward the under-side thereof; and

55 Fig. 9 is a perspective view of the thrust-stud.

The particular multiple-barrel firearm herein chosen for the illustration of the present invention is of that class commonly referred to as "over-and-under" firearms, in which the barrels are arranged one over another. The firearm in 5 question includes a butt-unit and a barrel-unit pivoted together, as is usual in breakdown firearms.

The butt-unit comprises in the main a frame generally designated by the numeral 20, and a 10 buttstock 21 rigidly secured to the rear end of the said frame. The barrel-unit above referred to comprises in the main an upper barrel 22, a lower barrel 23 and a forestock 24, which latter is provided with a forestock-shoe 25 bearing 15 against the cylindrically-contoured forward end 26 of the frame 20 in the usual manner of breakdown firearms. The barrel-unit may be rocked with respect to the butt-unit from the position in which it is shown by full lines in Fig. 1 to the 20 position in which it is indicated by broken lines in the same figure, and vice versa. The rocking movement referred to takes place about a pivot-pin 27 carried by the frame 20 and arranged concentrically with respect to the cylindrically-contoured forward end 26 of the said frame. 25

The frame 20 is "hollowed out," so to speak, to provide a chamber 28 immediately to the rear of its standing-breech 29 and has rearwardly projecting from its respective upper and lower walls 30 a pair of substantially-parallel spaced-apart tangs 30 and 31 which are connected together at their rear ends by a substantially-vertical tie-bar 32.

35 Directly below its forwardly-facing standing-breech 29, the frame 20 is provided with a bottom passage 33 normally closed by a removable cover-plate or closure 34 through which various machining operations may be carried on within the interior of the chamber 28 of the frame prior to the 40 installation of the said cover-plate 34, and through which various features of the mechanism may be introduced, removed or adjusted.

Extending through the standing-breech 29 and 45 through portions of the respective opposite side-walls 35—35 of the said frame 20 is a pair of longitudinal guide-ways 36—36 respectively receiving cylindrically-contoured locking-bolts 37 and 38, each of which has reciprocating movement and capacity for slight turning movement 50 in the particular one of the bearing-passages 36 in which it is mounted.

The forward end of each of the guide-ways 36 intersects a vertically-extending arcuate notch or recess 39, one of which is formed on each of the 55

respective opposite sides of the transverse center line of the gun structure, as indicated particularly well in Fig. 5. Normally projecting into the recesses or notches 39, just referred to, are locking-lugs 40-40, rearwardly projecting from the barrel-unit of which the upper and lower barrels 22 and 23 constitute the main features. The upper surfaces of the locking-lugs 40-40 are inclined slightly downwardly and rearwardly for engagement respectively by the similarly-sloping under-faces 41-41 of locking-noses 42-42 of the said locking-bolts 37 and 38.

Adjacent its rear end, the locking-bolt 37 is formed with an inwardly-opening cylindrical socket 43 receiving, with freedom for slight relative movement in all directions, a cylindrically-contoured trunnion-like projection 44 offsetting laterally from a coupling-slide 45. The opposite side of the coupling-slide 45, just referred to, is also provided with a cylindrically-contoured projection or trunnion 46, fitting within, with freedom for slight relative movement in all directions, a notch-like socket 47 inwardly and downwardly opening from the rear portion of the locking-bolt 38.

The coupling-slide 45 above referred to is provided with a rearwardly-projecting guide-tail 48, loosely fitting and reciprocating, with capacity for slight rocking movement, in a guide-passage 49 formed in a bridge-piece 50 extending vertically between the respective upper and lower tangs 30 and 31 of the frame 20. The rear end of the guide-tail 48 of the coupling-slide 45 is adapted to engage with and rearwardly shift a slide-bar 51 which is adapted to rearwardly shift a manually-operable safety-slide 52 located upon the upper surface of the upper tang 30 and having a stem 53 extending inwardly through a passage 54 in the said tang and coupled in any suitable manner to the rear portion of the slide-bar 51 before referred to.

The coupling-slide 45 is also provided with a laterally-opening coupling-notch 55 receiving a coupling-pin 56 depending from the under side of the head 57 of an operating-lever 57^a, through a clearance-passage 57^b in the top wall of the frame 20, and having an upstanding finger-piece 58 overlying the upper tang 30 of the frame 20. The head 57 at the forward portion of the operating-lever 57^a is located in a rearwardly-opening recess 59 formed in the frame 20 just to the rear of the standing-breech 29 thereof, as indicated particularly well in Figs. 1 and 2. The said recess 59 is surrounded on its front and side portions by a substantially-semi-circular upwardly-facing seat 60, against which rests a retaining-cap 61 also engaging with the upper face of the head 57 of the operating-lever 57^a and retained in place by means of a screw 62 extending upwardly thereto, as indicated in Fig. 1. Adjacent its right side, the head 57 of the operating-lever 57^a is provided with a depending cylindrically-contoured fulcrum-pin 63 turning in a suitable socket 64 formed in the upper wall of the frame 20.

At a point adjacent the end wall of its coupling-notch 55, the coupling-head 45 is provided with a vertical socket 65 receiving, with freedom for turning movement, the cylindrical shank 66 of a thrust-stud 67 having a horizontal passage 68 through its head portion 69. Bearing in the passage 68 of the thrust-stud 67, just referred to, is the forward end of a guide-rod 70 having a rigid annular spring-seat 71 adjacent its rear end, against the forward face of which a spring 72 seats. The forward end of the spring 72 just

referred to bears against the rear face of the head 69 of the thrust-stud 67 and exerts a constant effort to move the same forwardly, and hence to bodily shift the coupling-head 45 forwardly, together with its complementary locking-bolts 37 and 38. The rear end 73 of the guide-rod 70 is pointed and constantly urged by the spring 72 into a forwardly-facing shallow socket 74 formed in the forward face of the bridge-piece 50.

It may here be noted that the spring 72, acting through the thrust-stud 67, not only urges the coupling-head 45 forwardly, but, also, urges the forward end of the same upwardly toward the under-surface of the upper-wall of the frame 20.

In assembling the locking mechanism prior to the installation of the removable bridge-piece 50, both locking-bolts 37 and 38 may be inserted in their respective guide-ways 36-36, with the locking-bolt 37 turned so as to face its cylindrical socket 43 obliquely downwardly. The trunnion 44 of the coupling-slide 45 may now be inserted into the socket 43 and the said slide then swung upwardly with the locking-bolt 37 as a center to enter the trunnion 46 into the downwardly-and-inwardly-opening socket 47 in the locking-bolt 38. After the bridge-piece 50 thrust-stud 67, guide-rod 70 and spring 72 have been installed, the forward end of the coupling-slide 45 will be urged upwardly, as well as forwardly, while the rear portion of the said coupling-slide will be supported by the riding of its guide-tail 48 in the guide-passage 49 in the said bridge-piece 50.

When the finger-piece 58 of the operating-lever 57^a is swung from left to right into the position in which it is indicated by broken lines in Fig. 2, such movement will take place about the fulcrum-pin 63, and the coupling-pin 56 of the said lever will act against the rear wall of the coupling-notch 55 of the coupling-slide 45 and force the same rearwardly against the yielding counter-urge of the spring 72.

The rearward movement of the coupling-slide 45, as above described, will, in turn, effect, through the intermediary of the trunnions 44 and 46, the simultaneous rearward movement of the locking-bolts 37 and 38, and, hence, withdraw the respective locking-noses 42-42 of the said bolts from engagement with and out of the path of the complementary locking-lugs 40-40 of the barrel-unit. The barrel-unit may now be swung with reference to the butt-unit into the position in which it is indicated by broken lines in Fig. 1.

When the barrel-unit is again restored to its normal position, as indicated by full lines in Fig. 1, and the locking-bolts 37 and 38 released for forward travel, the respective locking-noses 42-42 thereof will be respectively reengaged with the locking-lugs 40-40 of the barrel-unit for holding the latter firmly in position for the firing of the arm.

By means of the construction above described, the respective locking-bolts 37 and 38 may turn about their longitudinal axes to automatically cause the under-faces 41 of their respective locking-noses 42-42 to make a satisfactory surface engagement with the upper-surfaces of the respective locking-lugs 40 of the barrel-unit. This independent automatic adjusting movement of the locking-bolts 37 and 38 compensates for variations in manufacture and adjustment, and is permitted by reason of the fact that the trunnions 44 and 46 fit the respective sockets 43 and 47 with a sufficient degree of freedom.

Furthermore, by reason of the freedom for relative movement of the locking-bolts 37 and 38

with respect to each other and with respect to the coupling-slide 45, other variations in manufacture are also compensated for. For instance, should the guide-ways 36—36 in the frame-structure not be in absolute parallelism, no binding action would occur.

As an incident to the rearward travel of the coupling-slide 45, the guide-tail 48 of the latter will be forced against the forward end of the slide-bar 51 with the effect of also moving the same rearwardly, together with the safety-slide 52 and other parts coupled thereto.

The invention may be carried out in other specific ways than those herein set forth without departing from the spirit and essential characteristics of the invention, and the present embodiments are therefore to be considered in all respects as illustrative and not restrictive, and all changes coming within the meaning and equivalency range of the appended claims are intended to be embraced therein.

What is claimed is:

1. In a locking mechanism for breakdown firearms, the combination with a locking-bolt mounted in the firearm-structure with capacity for both reciprocation and turning movement therein about its longitudinal axis; spring-means urging the said locking-bolt into its locking position; a pivoted manual operating-member for retracting the said locking-bolt; and a reciprocating coupling-member connected to the said manual operating-member for being moved thereby and loosely connected to the said locking-bolt in such manner as to permit the said locking-bolt to turn about its longitudinal axis with respect thereto to accommodate itself to a member to be locked.

2. In a locking mechanism for breakdown firearms, the combination with a locking-bolt mounted in the firearm-structure with capacity for both reciprocation and turning movement therein about its longitudinal axis; spring-means urging the said locking-bolt into its locking position; a pivoted manual operating-member for retracting the said locking-bolt; and a reciprocating coupling-member loosely connected to the said manual operating-member for being moved thereby and also loosely connected by means of interengaging socket-and-trunnion means to the said locking-bolt in such manner as to permit the

said locking-bolt to turn about its own longitudinal axis with respect thereto to accommodate itself to a member to be locked.

3. In a locking-mechanism for breakdown firearms, the combination with a pair of locking-bolts mounted in the firearm structure with capacity for both reciprocation and independent turning movement therein; each of the said locking-bolts being provided with a socket, one of least of which is of downwardly-opening notch-like form; a coupling-member connected to the said manual operating-member for being moved thereby and provided with two trunnions respectively entering the sockets in the said locking-bolts to connect the same to the said coupling-member for operation by the said manual operating-member; and spring-means constructed and arranged to urge the said coupling-member forwardly and to urge the same upwardly to maintain one of its trunnions in the downwardly-opening socket of one of the said locking-bolts.

4. In a locking-mechanism for multiple-barrel breakdown firearms, the combination with a pair of spaced-apart cylindrical locking-bolts, each of which is mounted in the firearm structure with capacity for turning movement about its longitudinal axis and longitudinal reciprocation; a coupling-member extending between and loosely coupled to each of the said locking-bolts; and a manual operating-member connected to the said coupling-member intermediate the points of connection of the latter with the said locking-bolts.

5. In a locking-mechanism for multiple-barrel breakdown firearms, the combination with a pair of spaced-apart cylindrical locking-bolts, each of which is mounted in the firearm structure with capacity for turning movement about its longitudinal axis and longitudinal reciprocation; a coupling-member extending between and loosely coupled to each of the said locking-bolts; a manual operating-member connected to the said coupling-member intermediate the points of connection of the latter with the said locking-bolts; and spring-means urging the said coupling-member forwardly, and through the latter simultaneously urging both of the said cylindrical locking-bolts forwardly.

ROY L. PARSELL,
Administrator of the Estate of Louis Stiennon,
Deceased.
